(57) **CLAIM**

The ornamental design for a plastic container, as shown and described.

DESCRIPTION

FIG. 1 is a top and right side perspective view of the plastic container;

FIG. 2 is a left side container and container base perspective view thereof;

FIG. 3 is a left side elevation view thereof;

FIG. 4 is a right side elevation view thereof;

FIG. 5 is a rear elevation view thereof;

FIG. 6 is a front elevation view thereof; and,

FIG. 7 is a plan view of the container base thereof.

The broken lines in the drawings showing the body of the plastic container illustrate the portions of the design that form no part of the claim.
